United States Patent Office.

CHARLES H. HELMS, OF POUGHKEEPSIE, NEW YORK.

Letters Patent No. 97,638, dated December 7, 1869.

IMPROVED MACHINE FOR TRIMMING THE HEELS OF BOOTS AND SHOES.

The Schedule referred to in these Letters Patent and making part of the same.

To all whom it may concern:

Be it known that I, CHARLES H. HELMS, of Poughkeepsie, county of Dutchess, and State of New York, have invented certain new and useful Improvements in Machines for Trimming Heels of Boots and Shoes; and do hereby declare the following to be a full, clear, and exact description thereof, reference being had to the accompanying drawings, in which—

Figure C shows the cutter-wheel constructed according to my invention.

Figure D is sectional view of same, on line *a b* of Fig. C.

Figures A and B are elevations of arrangement of cutter-wheel and sand and rasp-wheels upon same shaft.

The object of my invention is to construct a cutter-wheel by which I can trim both sides of the heel to a boot or shoe, without the boot passing to different persons, or employing a different wheel; that is, I wish to trim both sides of the heel upon one wheel. This I can do upon wheel in Fig. C, or its equivalent, *h*. And

The nature of my invention consists in a double cutter-wheel, having a double-faced shoulder at the centre of the surface, so that the heel may be half trimmed upon one side of the wheel, the bottom of the heel bearing against one face of shoulder, and the other side of the heel trimmed on the opposite.

In the drawings—

h *h'* represent the cutter-wheel, provided with adjustable cutters *c* *c'* and double-faced shoulder *g*.

The advantage of this construction enables me to trim one side of the heel, from front to centre of back,

upon one side of cutter *h'*, and the other side turned and trimmed by the same workman, the shoulder *g* keeping the heel to the proper position.

The wheel *h'*, shown upon the shaft *S*, is an equivalent construction, but does not do the work so well nor so easily as *h'*.

The arrangement of cutter-wheels, sand and rasp-wheels upon the same shaft, is simply a convenient arrangement, but does not partake of the nature of an invention, nor do I claim any.

I am aware that burr-wheels with guide have been made and patented, but they are old, and I claim nothing of the kind; but I am not aware that a cutter-wheel, as shown in Fig. C, was ever used or constructed; and it meets a want in shoe-manufactories.

The wheel *h'* is whole, and the shoulder is fast with the wheel.

The arrangement of the adjustable cutters *c* is not new.

The sand-wheel *W* may be constructed in same form as cutter-wheel *h'*, to great advantage.

What I claim as my invention, and desire to secure by Letters Patent, is—

The double cutter-wheel *h'*, having double-faced shoulder *g*, and provided with adjustable cutters, substantially as set forth.

In testimony whereof, I have hereunto set my hand, this 23d day of October, 1869, in presence of two subscribing witnesses.

C. H. HELMS.
